RING HAMMER MILL

Stanley Denton Hartahorn, Philadelphia, Pa., assignor to Pennsylvania Crusher Company, Philadelphia, Pa., a corporation of New York

Application July 17, 1936, Serial No. 91,979

9 Claims. (Cl. 83—11)

This invention relates to crushing equipment, and more particularly to that class of equipment known as ringhammer mills, adapted for crushing or breaking coal and the like.

5 The principal objects of this invention are to provide an effective crushing machine in which a minimum of "fines" is produced and in which wear of the parts is minimized. These objects are carried out according to this invention by 10 developing the required crushing force at a moderately low machine speed.

The crushing machines according to this invention comprise a system of rotating hammer rings within a perforated cage enveloping the 15 rings. The perforated cage is preferably constructed of bars against which the material is crushed by the action of the hammers, the broken material passing out of the cage between the cage bars.

20 According to a feature of the invention the hammer rings are carried by a plural support. This has the effect of increasing the crushing force beyond that which can be obtained by the use of a single support. Hence for any required 25 crushing force the machine can be driven slower than in the case of single support. The slower speed produces a more gradual crushing force with a resulting smaller proportion of fines and reduced wear of parts.

30 In one form of the invention the hammer rings are carried on a supporting surface, such as a cam. In another embodiment they are carried on pairs of supporting bars.

35 The invention will be better understood from the following detailed description of specific embodiments, with reference to the accompanying drawings, of which:

Fig. 1 is a front view, in section, at line 1—1 of Fig. 2, of a machine embodying this invention;

Fig. 2 is a side view, in section, at line 2—2 of Fig. 1, of the same machine;

Fig. 3 shows a vector diagram of the forces on a ring hammer of the machine in Figs. 1 and 2;

45 Fig. 4 shows for comparison a vector diagram of the forces on the same ring hammer when provided with only a single support;

Fig. 5 shows a heavier type of ring also adapted for two point support;

50 Fig. 6 illustrates a machine embodying the invention in which the ring hammers are carried on a supporting surface;

Fig. 7 shows another embodiment of the invention which makes use of triangular shaped 55 rings;

Fig. 8 illustrates an embodiment which utilizes large triangular shaped rings carried on pusher cams mounted on the driving shaft;

Fig. 9 shows an embodiment in which the rings are scalloped and carried by the center driving shaft and a pusher bar;

Fig. 10 shows an arrangement similar to that of Fig. 9 in which the rings are triangular and not scalloped;

Fig. 11 shows another modification in which 10 hammer rings are supported over pusher cams keyed to the main shaft;

Fig. 12 shows a suspension arrangement for a ring hammer which may be substituted for those illustrated in other figures of this application; 15

Figs. 13 to 15 illustrate arrangements for mounting impact hammers on ring shanks which are carried by supporting systems according to this invention; and

Figs. 16 and 17 illustrate serrated ring hammers which may be used in connection with the several embodiments of this invention.

The machine shown in Figs. 1 and 2 comprises a frame 10 of suitable strength to support and enclose the machine. Supported within the 25 frame is a cage formed by an arcuate screening member 11, a breaker plate 12 and the walls 13 and 14 of a feed chute. At the side of the cage opposite plate 12 there is formed a pocket 15 for collecting tramp iron and the like. This 30 pocket is formed by the side wall of frame 10, a lower pocket plate 16 and an upper pocket plate 11.

The screening section 11 is formed by a frame of arcuate ribs shown at 18, to which are fastened longitudinally extending screen bars 19 providing screening spaces 20 therebetween. The arcuate section 11 is pivoted on a pivot shaft 21 at one side and is supported at the opposite side by a pivot 22 to which is attached a lever arm 40 23 fastened to a lever shaft 24. Shaft 24 may be turned by any suitable device, such as a handle, so that the position of the screening section 11 may be adjusted on its pivot shaft 21.

The machine is provided with a rotating hammer mechanism as follows: A shaft 30 extending longitudinally through the cage is mounted at the ends in bearings 31 and 32, of which bearing 31 is illustrated in detail. This is a roller thrust bearing having rollers 33, an outer roller guide 34 held within the hub of the bearing, and an inner roller guide 35 forced over a tapered part of shaft 30 by a nut 36. Dust rings 37 and 38 are provided at each end of the bearing to keep out dust and grit.

The hammer mechanism comprises a number of flanges 38 regularly spaced along the shaft, within the cage, by spacer collars 40. The last flange abuts against the collar 41 which is integral with the shaft. The assembly of the flanges 38 and spacer collars 40 is held tightly in position against collar 41 by suitable means at the opposite end, such as a nut (not shown).

A set of suspension rods 42 and a set of pusher rods 43 extend longitudinally through suitable holes in the flanges 38 at regularly spaced intervals around the circumference of these flanges, and are fastened in place in a suitable manner. The diameter of the circle of pusher rods 43 is somewhat greater than that of the circle of suspension rods 42, but each rod 43 is located quite close to its associated rod 42. Ring hammers 44 are placed over each adjacent pair of rods 42 and 43 within the spaces between the adjacent flanges 38.

In operation, the hammer shaft 30 is rotated by an external source of power (not shown). When shaft 30 is rotating the rings 44 fly outwardly due to centrifugal force into the positions illustrated. Each rod 43 is so situated that it just touches the inner periphery 45 of its associated ring when the radius r through the center of shaft 30 and of rod 42 coincides with the diameter of the ring. Under this condition, the rods 42 bear substantially all of the centrifugal force of their respective rings. Pusher rods 43 bear no appreciable force until the rings are resisted by material in the cage, in which case they serve to push the rings in their direction of motion. In this embodiment rod 43 touches the ring at a point about 90° from the point of contact with rod 42; although the 90° spacing is not essential.

The material to be broken is fed through the feed chute into the cage. The rotation of the hammer shaft causes the ring hammers 44 to extend out radially into the position shown so that they strike masses of the material which have dropped from the chute, crushing them against breaker plate 12 and the cage section 11, thereby breaking up the material. Those pieces of the material which are broken small enough pass through the spaces 28 between the screen bars and drop into a suitable receptacle below. Unbreakable material such as tramp iron is carried around and thrown into the pocket 15 from where it is removed from time to time.

Since the tramp iron pocket is at the left in Fig. 1, the direction of rotation of the shaft 30 must be clockwise with reference to this figure.

The movable screening section 11 is susceptible of adjustment to regulate the distance between the screen bars and the rotating hammers. To move the cage section closer to the hammers, it is only necessary to turn crank 28 to rotate lever arm 23 upward. By this device compensation for wear or a desirable adjustment for producing a satisfactory breaking operation may be obtained.

Figs. 3 and 4 show a comparison of the crushing action of the double support system of Figs. 1 and 2 and a single support system, the double system being illustrated in Fig. 3 and the single system in Fig. 4. As these figures give a general example the rods 42 and 43 are not shown exactly 90° apart around the inner periphery of the ring. In Fig. 3 the ring 44 is shown after striking a mass 46 of the material, which is compressed and crushed between the ring and the screen bars. Under this condition the ring is being pushed in its direction of rotation by the pusher bar 43. If the material

offers great resistance the ring may be lifted from the normal position shown at dotted line 44a, out of contact with the suspension bar 42, as shown. If any such lifting occurs the original perpendicular diameter d of the ring swings back through an angle u to the position D. The centrifugal force exists along the line through the centers of shaft 30 and of the ring 44, which coincides with diameter D, and is represented by the vector a . The pushing or driving force due to pusher bar 43 is along the line through the center of ring 44 and the point of contact of the pusher bar with the inner surface of the ring, and is represented by vector $-b$. The total crushing component of force is the vector difference of vectors a and $-b$, and is represented by the vector c . The net radial crushing pressure is represented by the vector f .

In the case of the single support of the hammer ring (Fig. 4), the ring must always swing back at least some distance upon striking material in order to overcome the resistance of the material, and for a given degree of resistance the angle u is greater than in the case of double support. The centrifugal force a_1 is directed along diameter D and is of the same magnitude as in Fig. 3; but diameter D in Fig. 4 is swung further back than in Fig. 3. The component of force on the suspension bar is then represented by vector $-b_1$, and the total crushing force on the material by the vector c_1 . The resultant radial crushing pressure is therefore the vector f_1 . The advantage of the double support is immediately apparent since vectors c and f are both considerably larger than vectors c_1 and f_1 . To develop a given crushing force, then, the machine can be driven slower in the case of the double support.

Fig. 5 illustrates a modification of the ring hammer which develops greater crushing force than the rings 44, for a given speed of rotation. In Fig. 5 the ring 48 is almost solid and is provided with a heart-shaped opening 49 for receiving the bars 42 and 43. The shape of the heart permits the ring to be raised from bar 42. Due to the greater weight of this solid ring, a machine containing it may be driven slower than one containing a lighter ring, and still develop the same crushing force.

Fig. 6 illustrates a ringhammer mill in which three rings 44 are arranged circumferentially around the hammer shaft 30. The entire machine is not shown, but simply a front view, in section, of the hammer mechanism and its relation to the screening section 11, shown in outline. Each of these rings is suspended on a cam-shaped supporting member 50 fastened on rods 51, and having a T-bead 50a extending over the periphery of the adjacent flanges 38. The members 50 provide arcuate supporting surfaces which support a considerable extent of the inner periphery surface of the rings. The ring supporting surfaces of members 50 are such that the inner ring peripheries just make contact therewith when the rings extend out radially in the normal direction of the centrifugal force.

When the rings strike masses of the material the members 50 act similarly to the two point supports previously described, and perform the functions of the suspension and pusher supports; and the rings may be lifted to the position shown by the dotted lines 44a when resisted by the material. This arrangement has good wearing properties because of the large supporting surfaces for the rings. Furthermore, owing to the presence of portions 50a, the flanges 38 may be made of smaller diameter than in the case of 35

Fig. 1 so that greater space is left for the material being crushed.

Fig. 7 illustrates another modification in which the ring hammers 65, mounted on two bars, 56 and 57, are approximately triangular. The rounded triangular shape results in a somewhat greater net radial crushing pressure inasmuch as the center of gravity is farther from the pivot when the ring is supported at one of its corners. The net radial crushing pressure is practically equal to the centrifugal force. It might be possible to use squares instead of triangles.

In Fig. 8 a single large round triangular shaped hammer ring 66 is used between a pair of flanges 39. These large rings are driven by cam shaped supporting members 61, somewhat similar to members 50 in Fig. 6, fastened to the hammer shaft 30. Members 61 have arcuate surfaces which conform with the shape of, and contact with, the inner surfaces of ring hammers 66 when extending radially outward in the normal direction of the centrifugal force.

This arrangement, like that of Fig. 6, is in effect another form of the two point support; and when the hammer rings strike masses of the material they may be raised somewhat from the suspension members 61 in the manner shown by dotted lines 60a.

In this form of crushing mill the several large ring hammers positioned along the shaft are preferably given different positions around the circumference so that the crushing resistance on the machine is substantially uniform. Two other of these large rings are shown at 60₁ and 60₂. With this arrangement a large ring may be used even though the machine is relatively small.

Fig. 9 shows a somewhat different ring hammer and manner of attachment. The ring 65 is suspended on the shaft 30 and is pushed by the pusher bar 66 suitably fastened to flange 39. To prevent the ring from slipping around during operation the inner periphery thereof is scalloped as shown at 67. Slipping can also be minimized by making the ring in a rounded triangular form as shown at 70, in Fig. 10.

Any desired number of rings of the form 65 or 70 may be used in the same hammermill spaced between flanges along the shaft, although only two are shown; and the rings may be placed in spaced angular positions around the shaft. When the rings are angularly spaced at intervals around the shaft the pusher bars 66 cannot be extended through all of the flanges 39, because of interference with the rings. The bars are therefore of the stub type extending between the two flanges containing the individual rings.

Hammer rings constructed and arranged according to Figs. 9 or 10 are advantageous for use in small mills. The relatively large hammers suspended on the main shaft 30 provide sufficient weight to develop a satisfactory crushing force.

Fig. 11 shows an arrangement of the ring hammers which avoids stubbing the suspension bars 66 in Figs. 9 and 10. Instead of individual suspension bars 66 within each individual ring, there is provided an individual cam 75 keyed to the shaft 30. Individual rings 77 are placed over the individual cams 75 between two adjacent flanges 39. Any number of these rings may be placed along the shaft, and they may be situated at different angular positions around the shaft as shown by ring 78.

Fig. 12 shows a ring suspension arrangement in which the normal direction of the centrifugal force causes the ring to contact only a suspension

bar, but not a pusher bar. This arrangement is applicable to a hammermill such as that shown in Figs. 1 and 2. In this arrangement the ring 44 is shown in contact with the suspension bar 42; but the pusher bar 43 is located within the hammer ring and out of contact with the inner periphery thereof. In this case the ring engages the pusher bar only after striking the material.

This idea of maintaining a pusher bar or surface normally out of contact with the ring may be used, if desired, in other embodiments of this invention, such as those shown in Figs. 5 to 7.

The principle of the ring hammers may, if desired, be applied to impact hammers. Fig. 13 illustrates an impact hammer 80 fastened to a 15 shank in the form of a ring 81 having a protruding tongue 82 carrying a pivot pin 83 to which the hammer is attached. The ring is hung over suspension rod 42 and pusher rod 43 as in the case of Fig. 1. The rod 43 is preferably located about 20 one-third the distance from the suspender bar 42 to the striking surface of the hammer. A pusher casting such as 50 in Fig. 6 could, of course, be substituted for the rods 42 and 43.

It is possible for the rings of Fig. 13 to rotate 25 without lifting away from rod 42 when the hammer strikes masses of material. This kind of rotation can be prevented, if desired, by scalloping the inside of the ring as shown in Fig. 9, or by using triangular ring shanks with suspension and 30 pushing arrangements such as those shown in Figs. 7, 8 or 10, or the heart shape as in Fig. 5. Fig. 14 is an example of an impact hammer pivoted to the tongue of a large triangular ring 84 somewhat similar to ring 66 of Fig. 8, suspended 35 on a cam-shaped member 81.

Another expedient would be positively to pivot the ring shank to rod 43 as shown in Fig. 15, wherein there is provided a lip 85 having a hole which fits over the rod. When the material offers heavy resistance to the hammer the ring can pivot on rod 43 and lift away from rod 42.

Inasmuch as the supported rings act very similarly whether used as hammers themselves or similarly as hammer shanks, the term "hammer ring" 45 is used in the specification to cover both cases.

It may sometimes be desirable to serrate the outer surfaces of the ring hammers. The serrations may take the form of spaced teeth 86 as shown in Fig. 16. These serve to draw the material more quickly into the machine, reducing slippage, and further, to disintegrate foreign material such as wood, gunny sacks, etc.

Fig. 17 illustrates an alternative form for the toothed serrations in which only the leading tooth 55 surfaces 87 are perpendicular to the circumference.

Serrations are not limited to use on circular ringhammers, but may be used also on other types such as the triangular.

I claim:

1. A hammermill comprising a rotary hammer system including annular hammers and means for individually supporting and propelling each hammer, said means including a propulsion element internally engaging the hammer at a forward point with respect to the direction of movement of the hammer, and a suspension element in position to engage the hammer internally at a point which is rearward and inward of said propulsion engagement with respect to said direction of movement of the hammer and which is to receive the centrifugal thrust on the hammer during idling rotation of the hammer system, the hammer being mounted for movement inwardly 75

5 suspension element upon crushing engagement with material to transfer the centrifugal thrust about the propulsion element and away from the of the hammer from the suspension element to the material; and a cooperating crushing chamber including a crushing wall extending along the hammer path arranged to hold material in position for crushing by the hammers.

10 2. A hammermill as set forth in claim 1 in which the hammer is provided with a central opening and the propulsion element and suspension element are located in the opening.

15 3. A hammermill as set forth in claim 1 in which the suspension element is positioned at an angular distance of the order of 90° from the propulsion element about the center of the hammer when in engagement with both elements, arranged to exert substantially the full centrifugal thrust of the hammer against the material when 20 the hammer is moved inwardly away from the suspension element upon crushing engagement with material.

25 4. A hammermill as set forth in claim 1 in which each hammer is substantially a solid disc cut away to receive the propulsion element and the suspension element.

30 5. A hammermill as set forth in claim 1 in which the hammer is provided with a central opening with a peripheral symmetrical series of depressions having the same spacing as the suspension element and propulsion element and adapted to engage said elements simultaneously.

35 6. A hammermill as set forth in claim 1 in which the hammer is provided with a central opening and the propulsion element and suspension element are connected by a curved surface arranged to engage the periphery of the opening.

7. A hammermill as set forth in claim 1 in which the suspension element is on the opposite side of the shaft axis with relation to the propulsion element.

8. A hammermill comprising a crushing chamber the walls of which comprise a screening cage, a hammer ring situated within said cage and adapted to be carried by a rotating shaft, said ring being supported at more than a single supporting point, a first supporting point being located at a further radial distance from said shaft and being further forward in the direction of rotation than a second supporting point, the inner periphery of said ring being provided with depressions having the same spacing as said supporting points arranged to prevent rotation of the ring when engaged at said points.

9. A hammermill comprising a crushing chamber, the walls of which comprise a screening cage, a hammer ring situated within said cage and adapted to be rotated around a shaft, a means for feeding material to be crushed into said chamber, said ring being supported by more than a single supporting element, a first supporting element being located at a further radial distance from said shaft and being further forward in the direction of rotation than a second supporting element, whereby said ring is pushed in its path of motion at said first element when said ring wedges material to be crushed against a wall of said chamber, said ring being formed as a disk which is solid except for a heart-shaped opening through which a support of each of said supporting points protrudes, the lobes of said opening being suitably spaced to constitute pivot seats for said supports.
